(57) **CLAIM**

The ornamental design for a balance vehicle, as shown and described.

DESCRIPTION

FIG. 1 is a front, right, and top perspective view of a balance vehicle showing my new design;

FIG. 2 is a front view of FIG. 1;

FIG. 3 is a rear view of FIG. 1;

FIG. 4 is a left side view of FIG. 1;

FIG. 5 is a right side view of FIG. 1;

FIG. 6 is a top view of FIG. 1; and,

FIG. 7 is a bottom view of FIG. 1.

The broken line portions of the balance vehicle in FIGS. 1-7 represent unclaimed portions of the claimed design and form no part thereof.

1 Claim, 7 Drawing Sheets
